US00D598444S

(12) **United States Design Patent**
Xie et al.

(10) **Patent No.:** US D598,444 S
(45) **Date of Patent:** ** Aug. 18, 2009

(54) **ALL IN ONE COMPUTER**

(75) Inventors: **Song-Tao Xie**, Shenzhen (CN);
Hong-Jin Wu, Shenzhen (CN);
Yun-Lung Chen, Taipei Hsien (TW)

(73) Assignee: **Hon Hai Precision Industry Co., Ltd.**,
Tu-Cheng, Taipei Hsien (TW)

(**) Term: **14 Years**

(21) Appl. No.: **29/321,294**

(22) Filed: **Jul. 14, 2008**

(51) **LOC (9) Cl. 14-02**

(52) **U.S. Cl. D14/336; D14/371**

(57) **CLAIM**

The ornamental design for “all in one computer,” as shown and described.

DESCRIPTION

FIG. 1 is a perspective view of the all in one computer showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of “all in one computer” is for the purpose of illustrating environmental structures only and forms no part of the claimed design.
